(57) **CLAIM**

The ornamental design for a ceiling fan light kit, as shown and described.

DESCRIPTION

FIG. 1 is a right side elevational view of a ceiling fan light kit showing my new design, the opposing right side elevational view being substantially the same thereof;

FIG. 2 is a bottom plan view thereof;

FIG. 3 is a top plan view thereof;

FIG. 4 is a top perspective view thereof; and,

FIG. 5 is a bottom perspective view thereof.

The broken lines in the views show environmental features, which are for illustrative purposes only and form no part of the claimed design.
